UNITED STATES PATENT OFFICE.

GEORGE M. HUBBARD, OF NEW HAVEN, CONNECTICUT, ASSIGNOR TO THE
W. & E. T. FITCH COMPANY, OF SAME PLACE.

DESIGN FOR A KEEPER FOR SASH-FASTENERS.

SPECIFICATION forming part of Design No. 32,815; dated June 12, 1900.

Application filed May 17, 1900. Serial No. 17,066. Term of patent 14 years.

To all whom it may concern:

Be it known that I, GEORGE M. HUBBARD, of New Haven, in the county of New Haven and State of Connecticut, have invented and 5 produced a new Design for a Keeper for Sash-Fasteners, (Case A,;) and I do hereby declare the following, when taken in connection with the accompanying drawings and the letters of reference marked thereon, to be a full, 10 clear, and exact description of the same, and which said drawings constitute part of this specification, and represent, in—

Figure 1, a perspective view of a keeper for a sash-fastener embodying my design; Fig. 15 2, a top view, and Fig. 3 a rear view, of the same.

This invention relates to a design for a keeper for sash-fasteners; and it consists in the configuration as hereinafter described, 20 and shown in the accompanying illustration.

As herein shown, the keeper consists of a lifting and drawing finger A, projecting forwardly and downwardly from the top or upper edge of a back plate B, which is formed at opposite sides with retaining-lugs C C, by 25 which it is secured in position. The edges of the finger merge into the back plate and the edges of the back plate merge into the retaining lugs or ends C, forming a symmetrical design. 30

I claim—

The design for a keeper for sash-fasteners, as herein shown and described.

In testimony whereof I have signed this specification in the presence of two subscribers. 35

GEORGE M. HUBBARD.
